D. L. CORTHELL

ADVERTISING DEVICE

Filed Nov. 15, 1923

UNITED STATES PATENT OFFICE.

D. L. CORTHELL, OF ST. JOSEPH, MISSOURI.

ADVERTISING DEVICE.

Application filed November 15, 1923. Serial No. 674,879.

To all whom it may concern:

Be it known that I, D. L. CORTHELL, a citizen of the United States, residing at St. Joseph, in the county of Buchanan, 5 State of Missouri, have invented a new and useful Advertising Device; and I do hereby declare the following to be a full, clear, and exact description of the invention, such as will enable others skilled in the art to 10 which it appertains to make and use the same.

The invention relates to advertising novelties and has for its object to provide a device of this character which may be used 15 for advertising subject matter, however is applicable to other subject matter. The device comprises hingedly connected cardboard members, on the inner sides of which may be printed advertising matter, or other 20 subject matter and means whereby when the hinged sections are moved apart to open position, a flag will be raised on one of the hinged members, against the action of a rubber, and through the medium of a cord 25 attached to the flag, and extending upwardly through an eye, and thence downwardly and through an eye, and having its end anchored to the hinged section opposite the flag carrying hinged section.

30 The flag is preferably raised adjacent and in registration with a printed flag pole on one of the hinged sections and the representation of a person in a position assumed during a flag raising operation.

35 With the above and other objects in view the invention resides in the combination and arrangement of parts as hereinafter set forth, shown in the drawing, described and claimed, it being understood that changes 40 in the precise embodiment of the invention may be made within the scope of what is claimed without departing from the spirit of the invention.

In the drawing:

45 Figure 1 is a perspective view of the device showing the same partially open.

Figure 2 is a side elevation of the device, showing the device partially open, and one of the hinged members broken away to 50 show the securing means.

Figure 3 is a perspective view of the lower end of the elastic member.

Figure 4 is a perspective view of the button to which the elastic member is attached.

55 Referring to the drawing, the numeral 1 designates a relatively stiff piece of card-

board, and 2 a similar cardboard, which is hingedly connected at 3 to the cardboard section 1, thereby forming a book or folder which may be opened or closed on its hinged points 3. Printed on the inner sides of the cardboard sections 1 and 2, may be any kind of subject matter for advertising or other purposes, however for purposes of illustration a school house 4 is shown. Printed 60 on the section 1 adjacent its free end 5 is a flag pole 6, adjacent which pole, a movable flag 7 is disposed and adapted to be raised to the top of the flag pole with the rear side 8 in registration with the flag pole. 65 The flag 7 is preferably formed from cardboard so that it will lay flat against the inner side of the cardboard section 1, when the cardboard sections are folded onto each other. Secured at 9 to the lower end of the 70 flag is an elastic member 10, which elastic member extends downwardly, and preferably terminates in a ring 11, which is received on the shank 12 of the fastener 13, which is secured to the section 1, and 75 against the action of which elastic member the flag 7 is raised to the top of the pole 6 by means of a cord 14, which cord is secured to the upper end of the flag 7 at 15. Cord 14 extends upwardly and through an 80 eye 16 carried by the cardboard section 1, adjacent the upper end of the flag staff 6 and then extends downwardly and through an eye 16^a adjacent the lower end of the flag pole and has its end anchored at 17 to 85 the cardboard section 2 adjacent its lower end and preferably spaced a substantial distance from the hinged portion 3 of the cardboard sections 1 and 2. By positioning the cord securing point 17, as above set 90 forth, it will be seen that when the sections 1, and 2 are moved to open position, an upward pull is imparted to the flag 7 thereby stretching the elastic member 10 as the flag moves upwardly. Said elastic member 100 forms means whereby when the cardboard sections 1 and 2 are folded against each other, the flag will be moved downwardly to lowered position adjacent the figures of the school teacher 18, who has her hands 19 positioned adjacent the flag pole 6 to give the impression that the school teacher is 105 raising the flag. It is obvious that the device may be used with different subject matter thereon, for instance the representation of a camp for boy scouts.

From the above it will be seen that a flag

raising device is provided which is particularly adapted as an advertising novelty, and on wherein upon opening of the device the flag will be raised, and upon closing the 5 flag will be automatically lowered.

It will also be seen that the device may be cheaply manufactured and sold, thereby allowing the device to be distributed as an advertising novelty.

10 The invention having been set forth what is claimed as new and useful is:—

15 1. A flag raising device comprising hingedly connected members, an elastic member having one of its ends anchored 20 to one of said hingedly connected members adjacent its lower end, a flag having its lower end connected to the upper end of the elastic member, a cord connected to the upper end of the flag, said cord extending upwardly through an eye adjacent the upper end of one of the hingedly connected members, thence downwardly and through an eye adjacent the lower end of said last

named section, the end of said cord being anchored to the other hingedly connected 25 member adjacent its free end.

2. A flag raising device, said device comprising hingedly connected members, a flag disposed on one of said hingedly connected members, the lower end of said flag being 30 connected to an elastic member anchored to the hingedly connected member, a cord connected to the upper end of the flag, said cord extending upwardly through an eye and thence downwardly and through an eye 35 adjacent the lower end of the section and thence across the hinging point of the hingedly connected members and anchored to the other hingedly connected member.

In testimony whereof I have signed my 40 name to this specification in the presence of two subscribing witnesses.

D. L. CORTHELL.
